CLAIM

The ornamental design for a selfie stick tripod, as shown and described.

DESCRIPTION

FIG. 1 is a front view of a selfie stick tripod shown in a fully extended configuration;

FIG. 2 is a front view thereof, shown with the selfie stick tripod in a fully compacted configuration;

FIG. 3 is a front view thereof, shown with the selfie stick tripod in a partially extended configuration;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a rear perspective view thereof;

FIG. 10 is an enlarged right side perspective view of portion 10 shown in FIG. 3;

FIG. 11 is a front view thereof, shown with the selfie stick tripod in a collapsed configuration;

FIG. 12 is a right side view thereof; and,

FIG. 13 is a left side perspective view thereof.

The broken lines encircling an enlargement portion of the design forms no part of the claimed design.
